United States Patent Office.

GEORGE DORN, OF ALBANY, NEW YORK.

Letters Patent No. 81,151, dated August 18, 1868.

IMPROVEMENT IN EGG-CARRIERS.

The Schedule referred to in these Letters Patent and making part of the same.

TO ALL WHOM IT MAY CONCERN:

Be it known that I, GEORGE DORN, of the city and county of Albany, State of New York, have invented a new and improved Mode of Holding and Carrying Eggs, whereby the eggs are better preserved from becoming stale or broken; and I do hereby declare that the following is a full, clear, and exact description thereof, reference being had to the accompanying drawings, forming a part of this specification, in which—

Figure 1 represents a perspective view of the invention.

Figure 2 is a vertical view of the same from the top.

Figure 3 is a longitudinal cross-section.

The nature of my invention consists of a number of trays or frames furnished with egg-spaces, placed about a quarter of one inch apart, more or less. The said egg-spaces are formed by weaving from side to side and from end to end, at right angles with each other, cords, twine, or rubber strips, or similar suitable substances, at proper distances apart, to bound the sides of the eggs. Three such woofs are used in one tray or frame. The uppermost woof has spaces woven large enough to admit the largest diameter of the eggs. The middle woof is placed about three-fourths of one inch below, and has its spaces large enough to bound the smaller diameter, below the centre of the eggs, while the lower woof, placed three-fourths of one inch lower, has its spaces just large enough to admit the small ends of the eggs.

Several of these trays or frames may be used in and with a crate or box, properly constructed to receive them.

To enable others skilled in the art to make and use my invention, I will proceed to describe it in reference to the accompanying drawings, and letters of reference marked thereon, the same letters indicating like parts.

A A, figs. 1, 2, and 3, represent a frame of an egg-tray, and is made of suitable material, and of such dimensions as may be thought proper to suit the user.

From side to side, both lengthwise and across, are woven the cords $c' c'' c'''$. The cords $c' c'' c'''$, running lengthwise, are woven alternately above and below the cords $c' c'' c'''$, which run across.

The spaces $s' s' s$, fig. 3, formed by the cords $c' c'$ crossing each other at right angles, as in figs. 1 and 2, are made of a size which will admit the largest diameter of an egg, while the cords $c'' c''$ are woven so as to afford spaces, $s' s'$, suited to a second diameter of the egg, about three-fourths of one inch below its centre. A third-size spaces, $s'' s''$, are woven by the lengthwise and cross-cords $c''' c'''$, to admit the smaller ends of the eggs E E.

The said egg-spaces $s' s' s'$, thus formed, present an outline of an inverted pyramidal form, and the cross-cords $c' c'' c'''$, which form the said spaces, and bound the several diameters of the eggs, support and steady the eggs by their contact with the said cords.

Smaller spaces, $x x$, are formed between the spaces $s' s'$, to keep the eggs apart.

Suitable cord or twine may be used, such as paper, cotton, flax, and the like; also rubber, gutta percha, tape, or wire may be used, if thought proper.

On the bottom of each tray-frame A, I tack a piece of canvas, (which canvas is not shown in the drawings, as I do not claim it as being new,) and when the trays are placed one on the other, the said canvas will press on the eggs in the tray below, and secure them in their places, when the crate is inverted. A similar canvas is stretched on a frame fastened on the inner side of the cover of the crate, to hold down the eggs placed in the top crate.

Several egg-trays thus constructed may be placed in a crate or box, similar to a strawberry or oyster-crate, in which the trays and their eggs may be carried to their destination with safety.

The advantages of this improvement over the old method of packing eggs and carrying them to market with oats, bran, chaff, and the like, are these:

No foreign material is needed to pack the eggs; children can be employed to place the eggs with safety; the eggs are always placed on their ends, as they should be for preservation; they are not liable to be broken by contact with each other; the dealer can show his customer that the eggs he buys are whole.

Having described my invention, what I claim, and desire to secure by Letters Patent, is—

The cords $c' c'' c'''$, of twine, rubber, or their equivalents, as described, woven and arranged substantially as described, for the purpose specified.

Witnesses:

ALEX. SELKIRK,
A. PALMATEER.
